UNITED STATES PATENT OFFICE.

IRWIN W. EISENBERG, OF ALHAMBRA, CALIFORNIA.

RADIO EQUIPMENT.

Application filed March 28, 1923. Serial No. 623,226.

My invention relates to the art of radio telephony, and relates particularly to an improvement in receiving sets whereby an increase in audibility and definition in tonal qualities may be attained in the use of standard detector equipment.

It is the object of the invention to provide a novel type of condenser having three poles instead of the ordinary two poles, this condenser being connected both in series with the secondary coil of the vario condenser and across the phones, or, in other words, across the audio circuit and across the phones.

15 It is a further object of the invention to provide a condenser which gives an increased capacity owing to the peculiar arrangement thereof, and which may be so connected in a radio receiving set that the sharpness and 20 the tonal qualities, as well as the intensity thereof, are greatly increased.

It is a still further object of the invention to provide an improved system of circuits in a radio receiving equipment, which system 25 incorporates my improved condenser.

The especial advantages of the invention and further objects thereof will be made evident hereinafter.

Referring to the drawing, which is for 30 illustrative purposes only:

Fig. 1 is an elevation of my improved three pole condenser.

Fig. 2 is a sectional view taken upon a plane represented by the line 2-2 of Fig. 1.

35 Fig. 3 is a section similar to Fig. 2 showing the manner in which the capacity of the condenser may be varied by rotating the rotatably mounted segments between the stationary segments.

40 Fig. 4 is a diagrammatic view illustrating the action which is produced within the condenser.

Fig. 5 is a diagram showing my improved radio receiving equipment in which my three 45 pole condenser is employed.

The condenser as shown in Fig. 1, is provided with an insulated base 11 having standards 12 and 13 made of fiber or other insulating material. Between the standards, 50 semi-circular condenser plates 15 and 16 are supported upon fiber rods 17, having spacing bushings 18 for holding the plates 15 and 16 in separated position. The plates 16, as shown in Fig. 2, are notched as indicated at 20, these notches being formed in

the edges thereof near the front side of the condenser. The plates 15, as shown in Fig. 3, are similarly provided with notches 21 which are rearwardly disposed. Through holes 22 provided in the plates 15 and 16 60 electro-conducting rods 23 and 24 are extended, which rods are provided with fiber spacing bushings or sleeves 25. The fiber spacers 25 extend through the notches 20 in such a manner that the plates 15 are kept from electrical contact with the rearward rods 24, and the plates 16 are held out of engagement with the forward rods 23.

It will be perceived that by this arrangement the plates 15 are electrically connected 70 through the forward rod 23 which has a binding post 27 mounted upon the leftward end thereof, while the plates 16 are electrically connected through the rearward rod 24 which has a binding post 28 mounted 75 upon the rightward end thereof. Semi-circular plates 30 are supported upon a shaft 31 in a position substantially concentric with the stationary plates 15 and 16. By rotating the thumb knob 32 mounted upon the shaft 80 31, the plates 30, which are of smaller diameter than the plates 15 and 16, may be rotated through the intermediate position shown in Fig. 2. In this manner the capacity 85 of the condenser may be varied by varying the area of extension of the plates 30 between the stationary plates 15 and 16. Upon the standard 12 a contact spring 35 is mounted which bears against the end of the shaft 31, and a binding post 36 is provided 90 whereby the plates 30 may be connected into a circuit.

In the diagram, Fig. 4, I show what I believe to be the capacity effects attained in the three pole combination I employ in my condenser. It is impossible for me to state with absolute finality the conditions produced within this condenser, but the theory herein-after set forth is the only explanation that I have, up to the present time, been able to 95 develop which will support the increase in capacity and improved tonal effects obtained in a radio receiving set when my invention is employed therewith. As illustrated in Fig. 4, the plates 30 extend between the plates 15 and 16. The plates 15 are electrically connected as indicated at 40 and the plates 16 are electrically connected as indicated at 41. It is evident that there will 100 occur in the use of the condenser a capacity 105 110

between the plates 30 and the plates 15, as indicated at 43, and that there will also be a capacity between the plates 30 and the plates 16, as indicated at 44. The fact that

5 the plates 15 and 16 are adjacently located and are connected with separate circuits would indicate that a condenser capacity, as indicated at 45, is created therebetween, this capacity being intermediate in its action and 10 serving to eliminate vicarious oscillations within the circuit.

In Fig. 5 I show my improved form of radio receiving set with which I employ the condenser hereinbefore described. In this 15 figure, 50 indicates an aerial which leads through the primary 51 of a vario coupler and through a variable condenser 52 to the ground 53. The receiving equipment shown in this figure is a combined direct and in- 20 ductant type in which a vacuum tube 54 of types similar in operation to the audion rectifier is employed. This rectifier is pro- 25 vided with a filament 55 which is adapted to be energized from a battery 56, having a rheostat 57 associated therewith. The open 30 circuit is connected to the filament by a conductor 58; and a conductor 59, having a condenser 60 therein, extends from the aerial lead to the grid 61 of the rectifier 54. The 35 audio or phone circuit employed with this device incorporates the secondary winding 65 of the vario coupler, conductors 66 ex- 40 tends to the plate 67 of the rectifier 54, a circuit 68 having a battery 69 therein and 45 extending to one side of the phones 70, and a conductor 71 extending between the op- 50 posite side of the phones 70 and the second- 55 ary vario coupler coil 65. My improved 60 form of condenser 73 has the plates 30 con- 65 nected into the conductor 71, while the plates 15 thereof are connected with the conductor 66, and the plates 16 connect into the conductor 68 at a point between the bat- 70 tery 69 and the phones 70.

45 The filament 55, when heated by electrical energy from the battery 66, radiates negative electrons which interfere with the negative flow of electricity in the audio circuit. The presence of the grid 61 in turn inter- 50 feres with the negative flow from the fila- 55 ment 55, so that the only electrical flow which can occur through the rectifier is in a positive direction, or, in other words, from the plate 67 to the filament 55. The tend- 60 ency of the battery 69 is to impound a steady positive flow of current through phones 70 and through the audio circuit. It will be seen that as the induced electrical charge in the audio circuit oscillates the positive flow 65 of electricity from the battery will be reinforced by positive impulses from the sec- 70 ondary 65, and will pass from the plate 67 to the filament 55, thence continuing through the audio or phone circuit. In this manner, 75 the variations in the intensity of the ether

waves received by the aerial 50 are made detectable in the form of sound vibrations at the phones 70.

Whenever current in the phone circuit os- 75 cillates in the direction indicated by the arrow 75, the plates 15 are charged with positive electricity and the plates 30 are negatively charged, likewise, the plates 16 being connected to the positive side of the battery 69 are also positively charged. It 80 will be seen, therefore, that during this posi- 85 tive flow in the phone circuit, the capacity of the condenser 30 attracts a certain por- 90 tion of the positive flow of electricity, which is released upon the changing of the flow in the secondary 65 to a negative, or in other words in reverse direction, thereby produc- 95 ing or reinforcing oscillations of current in the phone circuit. In other words, separate oscillating circuits are set up through the condenser, one of these circuits being com- 100 prised of the plates 16 and 30, the conductor 75, the phones 70, and the conductor 76. When the flow through the secondary 65 re- 105 verses, as hereinbefore described, the plates 15 and 16 become negatively impressed, while the plate 30 becomes positive, there- 110 upon a reverse oscillation is produced through the phones 70, this reversed flow through the phones 70 acting against the positive flow of the battery therethrough, which has the effect of reducing the mag- 115 netic action within the phones caused by the positive flow of electricity from the battery 69, thereby causing a considerable increase in the amplitude of vibration attained in the phone diaphragm. The plates 15 and 30 act in combination as a condenser across the secondary 65 and create oscillations in 120 this circuit. The capacity between the plates 15 and 16 also comes into effect and assists in producing clear audibility and definition in tonal qualities. I have found that by the use of my improved condenser, an ordinary vacuum tube receiving equipment can be 125 given an increased efficiency of 25 to 50% in sharpness, or definition, quality, and intensity of sound produced therein.

115 Although the condenser has its particular application as herein described, it may be employed in various other manners in radio and telephone equipment, and I therefore desire that it be limited in scope only by the appended claims.

120 I claim as my invention:

1. In a condenser, the combination of: a series of primary plates connected by a single conducting means; and separate series of secondary plates, the plates of each sepa- 125 rate series being disposed alternately adjac- ent and connected together, and each series being insulated from the other.

2. In a condenser, the combination of: a series of primary plates connected by a single conducting means; separate series of 130

secondary plates, the plates of each separate series being disposed alternately adjacent and connected together, and each series being insulated from the other; and means for providing relative movement between the primary series and secondary series of plates for the purpose of varying the capacities thereof.

3. In a condenser the combination of: a series of primary plates mounted upon a shaft and electrically connected thereby; and separate series of secondary plates mounted so that said plates are interposed between said primary plates, alternate plates of the secondary series being insulated from the intermediate plates of the secondary series and electrically connected, the plates of the secondary series all being insulated from the plates of the primary series.

4. In a condenser the combination of: a series of primary plates mounted upon a rotatable shaft and electrically connected thereby; and separate series of secondary plates mounted relatively stationary and so that said plates are interposed between said primary plates, alternate plates of the sec-

ondary series being insulated from the intermediate plates of the secondary series and electrically connected, the plates of the secondary series all being insulated from the plates of the primary series.

5. In a condenser the combination of: a supporting member having oppositely disposed arms; a shaft extended between said arms; a series of semi-circular primary plates mounted upon said shaft and electrically connected thereby; secondary plates supported on said arms and regularly spaced thereon intermediately of said primary plates, alternate plates of said secondary series being insulated from the intermediate plates of the secondary series and electrically connected, the plates of the secondary series all being insulated from the plates of the primary series; and means for relatively moving the primary and secondary plates for the purpose of varying the capacities thereof.

In testimony whereof, I have hereunto set my hand at Los Angeles, California, this 21st day of March, 1923.

IRWIN W. EISENBERG.
